FIG. 3.

19 26 J. A. CORBETT.

Leffler & Wilcox Attorney

UNITED STATES PATENT OFFICE.

JOHN A. CORBETT, OF LOS ANGELES, CALIFORNIA.

SHOW CASE.

Application filed September 13, 1922. Serial No. 587,937.

To all whom it may concern:

Be it known that I, JOHN A. CORBETT, of Los Angeles, in the county of Los Angeles and State of California, have invented certain new and useful Improvements in Show Cases; and I do hereby declare the following to be a full, clear, and exact description of the invention, such as will enable others skilled in the art to which it appertains to 10 make and use the same.

My invention relates to improvements in show cases.

The object of my invention is to provide a show case in which the goods are displayed in a slanting position so that they may be readily seen by the customer, and yet protected from handling and at the same time providing means for moving the support rearward, and tilting it is a reverse direction, and supporting it in said tilted position so that the goods can be readily removed from the original containers or compartment by the salesman.

Another object of my invention is to provide a show case in which the goods can be readily displayed in their original containers, and at the same time providing a simple and effective structure having certain details and combination of parts hereinafter more fully pointed out.

In the accompanying drawings:

Fig. 1 is a perspective view of a show case embodying my invention.

Fig. 2 is an enlarged perspective view of one compartment showing the sliding and tilting support for holding a container.

Fig. 3 is a transverse sectional view of Fig. 2.

Referring now to the drawings, 1 and 2 represent the two base boards or feet to which are connected the two standards 3 and 4, connected at their upper ends by the cross bars 5. Supported by the standards 3 and 4 are a series of shelves 6, 7 and 8, arranged 45 at an angle or slanting towards the front of the case. Connected to the base boards or feet 2 and 3, are two uprights 9 and 10, which are connected to the ends of the shelves adjacent the front face forming an 50 additional support therefor. The front of the shelves are closed as indicated at 11 to hold the goods thereon, and is provided with a series of vertical transverse partitions 12 forming the individual compartments for 55 the different kinds of goods to be displayed. The bottom of the compartments, as shown,

are preferably open so that the dirt will not collect in the bottom. Extending across the inner edge of the shelf is a strip 13, which braces the partition, and also may serve as 60 a support for a glass cover when the same is used.

In the description of the sliding and tilting tray, I will refer to Figures 2 and 3 of the drawings, as each compartment is exactly alike. The two side walls 14 and 15 of the compartment are provided with oppositely arranged slots 17 and 18 extending at an angle to the lower edge 19. The outer ends of the slots 17 and 18 are flared or enlarged as indicated at 20, the purpose of which will be later described. The inner ends of said slots terminate in the enlarged portions 21, and the side walls have oppositely arranged slots 22 and 23, which extend parallel with the lower edge 19 of the compartment, and said slots 22 and 23 do not extend all the way to the inner edge of the compartment, as shown in Fig. 3. Extending across the lower edge of the compartment is a plate or strip 24, which serves as a support for the sliding tray 25, as shown in Fig. 2 of the drawings. This strip, as shown in Fig. 1 of the drawings, is continuous from one end of the shelf to serve as the support 80 for all of the trays on the shelf. The slots 22 and 23 are preferably made by the strips 26, secured to the lower edge of the partitions forming the compartments, and thus one strip serves for two compartments. 85 These strips also give a more firm support for the sliding tray to hold it in any of its positions, as shown in Fig. 2 of the drawings.

The tray 26 consists of a rectangular 95 frame having at its front edge an upwardly extending ledge 27, which serves as a stop to prevent the drawer or container from sliding therefrom when the tray is tilted, as shown in Fig. 2 of the drawings. The said 100 tray at the side adjacent its rear edge is provided with outwardly extending pins or lugs 28 and 29, which enter the slots 22 and 23, and allows the tray to be moved in and out in the shelf. The tray at the sides adjacent 105 its outer edge is provided with the lugs 30, which are of a size to freely slide in the slots 17 and 18 when the tray is in the shelf in a position to display the goods.

From the foregoing description, it will be 110 seen that the tray is pulled out in the position shown in Fig. 2, when the salesman de-

sires to remove any of the goods which may be in the original containers, or may be placed in specially constructed receptacles adapted to rest upon the tray or formed integral therewith.

When it is desired to return the tray to its normal position, it is forced inwardly until the lugs 28 and 29 come opposite the enlarged recesses 21, which allows the outer end of the tray to be raised so that the lugs 30 will enter the flared ends 20 of the slots 17 and 18, and then moved inwardly until the inner edge of the tray engages the front wall of the shelf, which brings the lugs 30 into the slots 17 and 18; said slots slanting downwardly, the tray is supported in its tilted or slanting position. In removing the tray, it is pulled outwardly a short distance to bring the lugs 30 out of the slots 17 and 18, and then lowered to rest upon the strips 24, which brings the lugs 28 and 29 opposite the slots 22 and 23, and then the tray can be moved outwardly until the lugs engage the ends of the slots which limits its outward movement.

25 Claims:

1. A show case comprising a compartment, a sliding tray therein, said compartment having two sets of slots having their rear ends communicating, and lugs carried by the rear end of said tray and adapted to travel in one set of slots, and lugs carried by the outer ends of the tray and adapted to travel in the upper set of slots whereby the tray may be supported in two tilted positions.

35 2. A show case comprising a compartment, a sliding tray therein, said compartment having two sets of oppositely arranged slots having their inner ends communicating, lugs carried by the inner end of the tray and travelling in one set of slots for holding the

tray in one tilted position, and lugs carried by the outer end of the tray and sliding in the other set of slots for holding the tray in a tilted position.

3. A show case comprising a compartment, 45 a sliding tray therein, said compartment having two sets of oppositely diverging slots, and lugs carried by the inner end of the tray and travelling in the lower set of slots for holding the tray in outwardly tilted position, and lugs carried by the outer end of the tray and adapted to travel in the upper set of slots for holding the tray in an inward tilted position.

4. A show case comprising a compartment, 55 a sliding tray therein, said compartment having two sets of oppositely arranged diverging slots, said tray having lugs entering one set of slots for supporting it in one tilted position, and lugs carried by the 60 tray and adapted to enter the other set of slots for supporting the tray in an oppositely tilted position.

5. A show case comprising a compartment, 65 a sliding tray therein, said compartment having two sets of slots starting together at the closed end of the compartment and diverging towards the opposite end, lugs carried by the inner end of the tray and adapted to slide in the lower set of slots to allow the 70 tray to be partially removed from compartment and tilted in one direction, and lugs carried by the outer end of the tray and adapted to enter the upper series of slots and support the tray in the oppositely tilted 75 position.

In testimony whereof I have signed this specification.

JOHN A. CORBETT.
